TIME LAG INTERLOCK

James W. Conklin, Rocky Point, N. Y., assignor
to Radio Corporation of America, a corpora-
tion of Delaware

Application December 20, 1934, Serial No. 758,408

8 Claims. (Cl. 200—122)

This invention relates to a time lag interlocking relay switch. An object of this invention is to provide a simplified and improved time lag relay switch which will be cheaper to manufacture, rugged in construction and yet maintain a fairly accurate control.

Another object of this invention is to improve the time control of an interlocking relay switch as is used in the circuit of a hot cathode rectifier tube used in a radio transmitter which would make it impossible to apply plate current to the rectifier tube until the filament has been sufficiently heated.

Another object of this invention is to overcome the defects in existing time lag relay switches wherein vibrations cause the switches to either operate at the right time, or fail to operate at such times as it is desired to be in an operative position. Such vibrations may be of a mechanical origin or may be due to magnetism caused by the close proximity of associated magnetic materials.

A feature of this invention is that the time of the interlocking relay switch is governed by design of a heating coil which can be regulated accurately by properly controlling the heating current.

Another feature of this invention is the mechanical arrangement incorporating the toggle link release principle, which has a minimum amount of friction and always exerts the same mechanical force against the thermostat element, thus providing an arrangement whereby considerable force can thus be positively locked and likewise released without much effort.

Another feature of this invention is the use of a bimetallic strip having a heating coil which entirely surrounds the bimetallic strip.

In the present-day use of hot cathode rectifiers of the mercury vapor type, it is necessary to prevent the application of plate current before the filaments have been sufficiently heated or reached the proper operating temperature. Therefore, in order to prevent such an occurrence, I have conceived this improved type of time lag interlocking relay switch which acts as an auxiliary switch to the main transmitter contactor or multi-actuated switches, at least one of said switches being arranged to make and break the plate circuit of the transmitter tube or tubes.

This invention will best be understood by referring to the accompanying drawing in which Fig. 1 shows a front elevation of improved time lag relay switch. Fig. 2 is a sectional view of Fig. 1. Fig. 3 shows an elementary wiring diagram of the time lag interlocking switch.

Referring now in detail to Figs. 1 and 2, 1 represents a base of insulation material having the necessary requisite insulating qualities to withstand the voltage through which this device is to be used in operation. Element 2 is a bimetallic strip which comprises the thermostatic or time lag element, which is arranged so that the material bends in the direction of the arrow 3 when sufficiently heated to give the desired time lag. A heating coil 4 is wound around the bimetallic strip and insulated therefrom by suitable insulation material 4a for the purpose of heating the strip to control the time lag in which this switch operates. 5 is a mechanical actuating button which is securely fastened to the bimetallic strip 2 at a position just above the heating coil 4. The bimetallic strip is supported by a base-like member 6 which is fastened to the main linkage support 7. Element 8 represents an adjustable support and stop element which is arranged to maintain the actuating button 5 and bimetallic strip 2 in a desired positive operating position, which position is such that any tendency to be upset by vibrations, etc., will be overcome. The contact relationship between member 8 and button 5 should be adjusted to a position which will require but a minimum force of a few ounces to set the actuating button in motion to open or close the groups of auxiliary contacts. The upper end of heating coil 4 is connected through the panel by an extending stud 9, the lower end being fastened by a screw 10 to make electrical connection to the supports 6 and 7, the connection through the panel being made by the stud-like member 11. Pivotedly located on the support member 7 is an adjustable link 12 of a toggle link system which is of metal or other suitable material. The upper portion of the adjustable link 12 is provided with a strip of insulating material 13 on which the mechanical contact button 5 bears in a position which is such that the pivot point between links 12 and 13 is slightly off dead center, and arranged to operate the upper portion of the linkage system when the bimetallic strip 2 is sufficiently heated and bends to cause the toggle link system to snap past the dead center position.

To the insulating member 13 there is fastened an L-shaped link member 14, which is pivotally secured to the panel by a support stud 15. The lower portion of member 14 carries an auxiliary or heater contact spring 16 which may be slightly bowed away from member 14 and is provided at its upper portion with a movable contact 17. The amount of curvature of the bowed part of spring 16

16 is about one-quarter of the total movement of members 14 at the point of contact of members 20, 21 and 22. The movable contact 17 in the position shown makes contact with a fixed contact 18 which is secured to the base 1 by a stud 19. The extreme upper portion of member 14 carries a plate circuit contact 20 which makes contact with a contact 21 which is fastened to the spring-like member 22 secured to panel 1 by means of a bolt 23. Electrical connection is made to the auxiliary or heater contact spring 16 by means of a flexible lead 24 which is secured to the support panel 1 by a bolt 25. Directly below the plate circuit contacts 20 and 21 there is pivotally secured to the member 14 a rod-like link 26, and secured thereto is an upright operating lever 27 which is actuated by the movement of a main radio transmitter line switch or magnetic contactor A or other suitable control motion which may comprise an electro-magnetic coil B, an armature C and a plurality of switch blades D. Contactor A moves the member 27 radially, either to the left or the right as indicated by the dotted lines. Between member 27 and member 14 there is provided a short coil spring 28, and on the other side of member 27 there is provided a long coil spring 29 which is securely fastened to the rod 26 by a washer 30 and cotter-pin 31. A reset spring 32 is fastened to the lower end of support 7 by means of the screws 33 and is always in frictional engagement with the link 12 at a point 34.

In the operation of this interlocking time lag relay, when the transmitter main control or multi-switch contactor A is actuated by energization of magnet B, armature C is moved inward toward panel 1, and carries with it in addition to the switch blades D the depending lever 27, and as member 27 is pivoted at point E, it moves outward and tries to pull the rod-like member 26 along with it, but is only able at this time to compress the long coil spring 29, as forward movement of rod 26 is prevented by the position of links 12 and 13. The resultant force which is transmitted through the lever 14 puts links 12 and 13 in compression, they being held out of the vertical line position by the reset spring 32, and are forced against the actuating button 5 which is secured to the bi-metallic thermostatic element 2, and thus prevented from moving forward at this time. Simultaneously with the above and by means of contacts 17 and 18 being closed, the transmitter vacuum tube heating current which may or may not be supplied through contacts D or other auxiliary contacts, such as switch 40, passes through a heating coil 4. The circuit arrangement of the filament heating current and its relationship with switch 40, is shown in Fig. 3. It will be noted that switch 40 has leads 36 and 39 connected in parallel therewith, so that when the supply current is connected to the filaments by means of switch S and switch 40 is closed, current passes through the bi-metallic heating coil 4, through leads 41 and contacts 17 and 18. When the bi-metallic strip is sufficiently heated to give the desired time delay, the internal forces set up against the bi-metallic strip will cause it to bend and move outward against link 12, forcing both links 12 and 13 outward and past the dead center position. As soon as members 12, 13 and 14 have moved past the vertical line of their dead center position, the system will then not be in equilibrium, and links 12 and 13 will quickly snap forward to the position indicated by the dotted lines, carrying with them member 14 and rod 26. At this time, contacts 20 and 21

will be closed, as a result of the position assumed by member 14, and held closed by spring 29. Also, auxiliary bi-metallic strip heater contacts 17 and 18 will open, thus opening the bi-metallic strip heater circuit and allowing bi-metallic strip 2 to cool sufficiently, thus returning to the normal position shown. The contacts 20 and 21 will be held securely closed by spring 29 until such time as the main contactor A is released. When main line contactor A or any other suitable control motion is reversed in operation by a release of energy in magnet B, spring 28 acts upon the system to force member 14 back to its normal position and the toggle links 12 and 13 are then reset to again bear against button 5 by the spring member 32.

Referring to the schematic wiring diagram, Fig. 3, the auxiliary or plate circuit is represented by the lines 36 and 37. The heater circuit is indicated by lines 38 and 39, and is connected in series with the plate switch 40, which may be one of the contactors of the main contactor A. The switch 40 is connected to the stud 19 supporting the fixed contact 18, an electrical circuit connection is made to contact 17 by way of spring 16. The position of contacts 17 and 18 is governed by the operation of the toggle link system, as explained above. The flexible lead 24 connects the heating circuit to the support member 7 by a bus 41; the heating coil 4 connects from the member 7 to the stud-like member 9, which is connected in the rear to line 39.

It will be apparent that this invention is not limited to the particular construction which is illustrated by the drawing and herein described, as it is capable of various other modifications without departing from the spirit of invention, as set forth in the appended claims.

I claim:

1. A time lag interlocking switch coupled to a main contactor having a plurality of contacts, said switch comprising a bimetallic strip, a group of auxiliary contacts linked to said main contactor, at least one contact of said group of auxiliary contacts being mounted on a movable member having means for actuating said movable member by an adjustable link forming one element of a linkage system linking said auxiliary contacts with said main contactor and arranged with said bimetallic strip to actuate said group of auxiliary contacts, a heating element surrounding said bimetallic strip to supply heat thereto, the heat causing said bimetallic strip to move and actuate the contact on said movable member when said bimetallic strip reaches a predetermined temperature.

2. A time lag interlocking switch coupled to a main contactor having a plurality of contacts, said switch comprising a bimetallic strip, a group of auxiliary contacts linked to said main contactor, at least one contact of said group of auxiliary contacts being mounted upon a movable member having means for actuating said movable member, an adjustable link forming a toggle release system linked to said main contactor and arranged with said bimetallic strip to actuate a pair of contacts, a heating element surrounding said bimetallic strip to supply heat thereto, the heat causing said bimetallic strip to move said toggle release system and actuate the contact on said movable member when said bimetallic strip reaches a predetermined temperature after movement of said main contactor.

3. A time lag interlocking switch coupled to a main contactor having a plurality of contacts,

- 5 said switch comprising a bimetallic strip, a group of auxiliary contacts, at least one contact of said group of said auxiliary contacts being mounted on a movable member, means for actuating said movable member by an adjustable link forming a toggle release system linking said auxiliary contacts with said main contactor, a plurality of springs arranged with said release system so as to 10 actuate said group of auxiliary contacts, a heating element surrounding said bimetallic strip to supply heat thereto, the heat causing said bimetallic strip to actuate the contact on said movable member when said bimetallic strip reaches a predetermined temperature.
- 15 4. A time lag interlocking switch coupled to a main contactor having a plurality of contacts, said switch comprising an arm extending out from said main contactor, a link member carrying auxiliary contacts coupled to said arm, a time delay release system coupled to said link member to 20 actuate said auxiliary contacts after a predetermined time has elapsed following the movement of said main contactor, said time delay release system comprising a toggle-like arrangement, a 25 bimetallic strip having a member bearing against said toggle-like arrangement, a heating coil surrounding said bimetallic strip to heat said strip sufficiently to move said toggle link when said predetermined time has elapsed after movement 30 of said main contactor.
- 35 5. A time lag interlocking switch coupled to a main contactor having a plurality of contacts, said switch comprising an arm extending out from said main contactor, a link member carrying auxiliary contacts coupled to said arm, a time delay release system coupled to said link member to 40 actuate said auxiliary contacts after a predetermined time has elapsed following the movement of said main contactor, said time delay release system comprising a toggle-like arrangement, a bimetallic strip having a member bearing against said toggle-like arrangement, a heating coil surrounding said bimetallic strip to heat said strip sufficiently to move said toggle link when 45 said predetermined time has elapsed after movement of said main contactor, and a reset spring bearing against said toggle-link arrangement to reset said auxiliary contacts.
- 50 6. A time lag interlocking switch which is mechanically coupled to a device for controlling motion comprising a bimetallic strip, a group of contacts, at least one contact of said group of con-
- tacts being mounted upon a movable member, means for actuating said movable member by an adjustable link forming a toggle link release system linking said device for controlling motion with said group of contacts, a plurality of springs arranged with said link release system to actuate said group of contacts, a heating element surrounding said bimetallic strip to supply heat thereto, the heat causing said bimetallic strip to move and allow one of said springs to actuate the 10 contact on said movable member when said bimetallic strip reaches a predetermined temperature, and means to adjust said bimetallic strip to alter the position thereof with respect to said toggle link release system.
- 15 7. A time lag interlocking switch which is mechanically coupled to a device for controlling motion comprising a base member having three link members secured to said base, the first of said link members being coupled to said device for controlling motion, the second of said link members coupled to said first link member, a pair of contacts located on each side of said second link, and an adjustable toggle link release system forming the third link which is coupled to said 20 second link member, said second link coupled to said first link member, a bimetallic strip having means to actuate said adjustable toggle release system, a heating element surrounding said bimetallic strip to supply heat thereto for releasing 25 said toggle link system and to actuate said contacts when said bimetallic strip reaches a predetermined temperature.
- 30 8. A time lag interlocking switch which is mechanically coupled to a main contactor having a plurality of contacts, said switch comprising a group of auxiliary contacts, at least one of said group of contacts being mounted upon a movable member and having means for actuating said movable member by a bimetallic strip, an adjustable threaded link member forming a toggle link release system linking said main contactor with said group of auxiliary contacts and arranged with said bimetallic strip to actuate a pair of said auxiliary contacts, a heating element 35 surrounding said bimetallic strip to supply heat thereto and to move said link release system to actuate the auxiliary contacts on said movable member when said bimetallic strip reaches a predetermined temperature.
- 40 45 50 J. W. CONKLIN.
